CLAIM

The ornamental design for drug administration safety label, as shown and described.

DESCRIPTION

FIG. 1 is a top plan view of one embodiment of a drug administration safety label of our new design, that portion shown in broken lines is not part of the claimed design and is provided for environmental purposes only.

FIG. 2 is a top plan view of an alternative embodiment of a drug administration safety label of our new design, that portion shown in broken lines is not part of the claimed design and is provided for environmental purposes only.

FIG. 3 is a top plan view of an alternative embodiment of a drug administration safety label of our new design, that portion shown in broken lines is not part of the claimed design and is provided for environmental purposes only; and,

FIG. 4 is a top plan view of an alternative embodiment of a drug administration safety label of our new design, that portion shown in broken lines is not part of the claimed design and is provided for environmental purposes only.
